CLAIM

(21) Appl. No.: **29/346,261**

The ornamental design for a combined puck light and pivoting mounting bracket, as shown and described.

(22) Filed: **Oct. 29, 2009**

DESCRIPTION

(51) LOC (9) Cl. **26-05**

FIG. 1 is a front perspective view of the puck light and pivoting mounting bracket of the present invention in an engaged configuration;

(52) U.S. Cl. **D26/63; D26/60**

FIG. 2 is a rear perspective view thereof;

(58) Field of Classification Search D26/28,

FIG. 3 is an exploded front elevation view of the combined puck light and pivoting mounting bracket showing the present invention in the disengaged configuration;

D26/37, 44, 60, 61, 63, 72, 80; 362/191,

FIG. 4 is an exploded rear elevation view thereof;

362/196, 197, 200, 396, 397, 473-476

FIG. 5 is a an exploded left side elevation view thereof with the right side being a mirror image thereof;

See application file for complete search history.

FIG. 6 is a bottom plan view thereof;

(56) **References Cited**

FIG. 7 is a top plan view thereof;

U.S. PATENT DOCUMENTS

FIG. 8 is a top plan view of the puck light portion of the combined puck light and pivoting mounting bracket, showing the present invention with the mounting bracket portion removed for illustrative purposes only; and,
